DESIGN FOR A BUCKLE

Silvia Dorée, New York, N. Y.

Application September 23, 1937, Serial No. 71,748

Term of patent 3½ years

To all whom it may concern:

Be it known that Silvia Dorée, a citizen of the United States and resident of New York city, in the county of New York, State of New York, has invented a new, original, and ornamental Design for a Buckle, of which the following is a specification, reference being had to the accompanying drawing, forming part thereof, and in which,

Fig. 1 is a front view of a buckle, embodying my new design;

Fig. 2 is a top end view thereof; and

Fig. 3 is a rear view of the same.

I claim:—

The ornamental design for a buckle substantially as shown.

SILVIA DORÉE.
